UNITED STATES PATENT OFFICE

FRANK E. BESSLER, OF AKRON, OHIO, ASSIGNOR TO THE BESSLER DISAPPEARING STAIRWAY COMPANY, OF AKRON, OHIO, A CORPORATION OF OHIO

DISAPPEARING STAIRWAY

Application filed February 23, 1929. Serial No. 342,023.

This invention relates to disappearing stairways of that type cooperating with a ceiling opening between lower and upper floors of a building.

One object of the invention is to provide an easily and safely operable disappearing stairway in which the stair structure may be carried by a movable ceiling panel which closes the ceiling opening and the stair structure is collapsible so as not to take up floor space on the upper floor when the stairway is retracted.

Another object of the invention is to provide power and control means for effectively operating disappearing stairways.

The foregoing and other objects of the invention are attained in the disappearing stairway illustrated in the accompanying drawings and described below. It is to be understood that the invention is not limited to the specific form and arrangement of the stairway shown.

Of the accompanying drawings,

Figure 1 is a side elevation, partly in section, of a stairway embodying the invention with the stairway in its position of use;

Figure 2 is a front elevation thereof, partly in section;

Figure 3 is a side elevation thereof, partly in section, with the stairway in its retracted position;

Figure 4 is an enlarged detail section of one side of the stairway on line 4—4 of Figure 1;

Figure 5 is an enlarged section on line 5—5 of Figure 2;

Figure 6 is a similar view of a portion thereof showing the parts in the positions they assume when the stairway is retracted as shown in Figure 3;

Figure 7 is a rear side elevation of the control mechanism as it appears in Figure 1;

Figure 8 is an enlarged view of the power and control mechanism as it appears in Figure 2; and

Figure 9 is a wiring diagram for the motor and control switches.

Referring to the drawings, the numeral 10 designates an opening in the ceiling between lower and upper floors of a building which

is arranged to be closed by a movable panel 11, preferably hinged at one end as at 12 and adapted to carry the stair structure 13.

The stair structure 13 comprises two sections 13^a and 13^b, each of which may be provided with hand rails 13^c and 13^d, hinged together on the under side thereof as at 14, the upper end of section 13^a being pivoted in the ceiling opening at 15 and the lower section 13^b having side grooves 16, 16 in which are fitted elongated slide blocks 17, 17 mounted on arms 18, 18 pivoted to brackets 19, 19 mounted on each side of the lower end of the panel 11. Bearing rollers are provided at 20, 20 on the arms 18 to support the lower stair section 13^b thereon so that it may slide freely on said arms. The lower end of section 13^b of the stairs may be provided with rollers 21 for engaging the lower floor when the stairway is extended to its position of use.

The stairway operating means includes cable drums 22, 22 preferably arranged at each side of the opening 10 adjacent the pivot for the stairway and preferably having the ends of a single cable 23 wound thereon, the cable extending from one drum over a sheave 24 on the same side of the ceiling opening, thence downwardly about a sheave 25 on the free end of an arm 18, thence downwardly along side of the lower section 13^b of the stair structure and about a sheave 26 mounted on one side thereof, thence across the stair structure to a corresponding sheave 26, thence upwardly along the other side of the stair structure to another sheave 25 on the free end of the other arm 18, thence upwardly about another sheave 24 on the other side of the opening and back to the other drum 22. The use of a cable connected across the stairway as shown serves to equalize the tension in the cable stretches on both sides of the stairway.

The power and control mechanism for operating the stairway may be of any known type, either power or hand operated, the particular mechanism herein shown being a novel type of mechanism for this purpose.

This power and control mechanism may be mounted as a unit in the ceiling opening above the panel hinges 12 and comprises a suitable

motor 27 connected through suitable reduction gearing 28 to reverse bevel gearing 29 controlled by a reversing clutch 30, the reverse gearing 29 being adapted to drive drums 22 which are secured on a shaft 31 through reduction gearing 32.

For starting motor 27, suitable switches 33 and 34 may be used of that well-known type usually provided with interconnected push buttons for operating an electrical device, such as a light in a building from two different points, these switches being mounted in convenient places for manual operation on the respective floors of the building between which the stairway is installed. To stop the motor, a suitable reversing switch 35 may be employed, this being shown in the drawings of standard form operable by a double-acting arm 35^a projecting from the switch box. The switches 33, 34 and 35 are arranged in the motor circuit as indicated in Figure 9 so that when the motor is stopped by the reversing switch, the latter sets connections between switches 33 and 34 so that a subsequent operation of either switch 33 or 34 will again start the motor.

The clutch 30 and cut-out switch 35 are arranged to be actuated by movement of the stairway into its extended position of use and into its retracted position. To stop the motor and reverse the clutch as the stairway is moved to its extended position, a slidable bar 36 is arranged in the housing 37 of the motor and control unit and normally projects outwardly of the casing into the ceiling opening so as to be engaged and depressed into the casing by abutment means 38 on the upper end of the stair structure as the latter moves into its completely extended position for use.

Bar 36 has a stud thereon at 39 cooperating with an arm 40 on a rock shaft 41 on which is secured a yoke arm 42 adapted to shift the shiftable member 30^a of reversing clutch 30. The shiftable clutch member 30^a has spaced apertured lugs 43 and 44 thereon through which is extended a fixed guiding rod 45 and the shifting force imparted to said clutch member 30^a is arranged to be yieldingly applied by provision of a block 45^a slidable on rod 45 by yoke arm 42 and having compression springs 46 and 47 arranged between it and lugs 43 and 44. Spring pressed dogs 48 and 49 are arranged respectively to engage in back of the lugs 43 and 44 as indicated at 48^a and 49^a in Figures 6 and 5 respectively to lock the clutch 30 in engagement in each of its reversed positions. The dogs 48 and 49 are adapted to be shifted out of such locking engagement when the clutch is to be reversed by engagement of inclined faces 45^b, 45^b on block 45^a therewith as shown in Figures 5 and 6 respectively. The shiftable clutch member 30^a also has spaced studs 60, 60 thereon for engaging the tumbler or operating arm 35^a of the automatic cut-out or reversing switch 35

to throw said switch in reversed directions.

To stop the motor and reverse the clutch when the stairway is retracted, a plunger 52 is arranged so as to project downwardly of the ceiling opening when the stairway is extended and to be pushed upwardly as the panel 11 shuts. The plunger is connected to a bell crank lever 53 which is connected by a link 54 to an arm 55 on rock shaft 41 to rock said shaft in the reverse direction (see Figure 7). Arm 40 cooperating with stud 39 on bar 36 and arm 55 cooperating through link 54 and bell crank 53 and plunger 52 are therefore so interconnected through the rock shaft 41 that when the plunger 52 or the bar 36 is depressed to stop the motor, etc., the other is projected into a position to be depressed to perform its corresponding function upon a succeeding operation of the stairway, either from its extended to its retracted position or vice versa.

In operation, when the stairway is in its retracted position and use thereof is desired, either of switches 33 or 34 are actuated starting the motor so as to pay out cable from drums 22. Panel 11 accordingly swings downwardly by gravity and the stair section 13^b slides by gravity on arms 18 and thus the stair structure as a unit swings downwardly about pivot 15 and the stair sections swing in the manner of a toggle into line with each other about pivot 14.

As the stairway moves into its position of use, abutment member 38 engages and shifts bar 36 which, through the mechanism described above, actuates switch 35 to stop the motor and throws clutch member 30^a into its reversed position in which it is held by dog 49, dog 48 being thrown out of its locked position shown in Figure 6 to position substantially as shown in Figure 5.

When the stairway is to be retracted after use, either of switches 33 and 34 are again actuated, starting motor 27 which drives drums 22 so as to wind the cable thereon. The first action of the cable is to swing arms 18 on their pivots whereby the toggle jointed sections of the stair structure swing about pivot 14 and section 13^b is drawn upwardly to collapse the stairway on the panel. When arms 18 swing into alignment with the cable stretches to the sheaves 24, the pull in the cable becomes effective on the panel and the panel moves upwardly carrying the collapsed stair structure thereon upwardly through the ceiling opening.

As panel 11 swings shut, it engages plunger 52 and through bell crank 53, link 54, arm 55 and yoke arm 42, releases dog 49 and actuates shiftable clutch member 30^a to operate switch 35 to stop the motor and to shift clutch 30 for a subsequent reverse operation.

It is to be understood that the reversing type switch 35 is used aside from stopping the motor merely to change the connections

between switches 33 and 34 so that the motor may subsequently be operated by either switch from either floor. The motor is always driven in the same direction, reversing of the movements of the stairway being accomplished through the reversing clutch.

It will appear from the foregoing that a simple, effective stairway construction has been provided which utilizes only the space above the ceiling opening on the upper floor when it is retracted and which can be safely operated between its extended and retracted positions with all parts of the stairway under complete control by the operating means. It is also apparent that a novel power operating means and controls therefor have been provided for stairways of the disappearing type.

Modifications of the invention may be resorted to without departing from the spirit thereof or the scope of the appended claims.

What is claimed is:—

1. A disappearing stairway comprising the combination with a movable panel closure for a ceiling opening, of a stair structure supported at its upper end so as to be movable with the panel, said stair structure comprising a single pair of sections pivoted to each other and supported on the panel so that the sections may be swung upwardly in inverted V-formation in the manner of a toggle and the lower end of the stair structure drawn upwardly onto the panel whereby the stair structure may move with the panel to a position in the ceiling opening above the panel when the panel is shut.

2. The combination with the ceiling of a lower room having an opening therein to give access to an upper room, of a stair structure supported at its upper end at said opening so as to be moved upwardly out of the way through said opening and comprising a single pair of sections pivoted to each other so that the stair structure may be collapsed to inverted V-formation in the manner of a toggle to pass through said opening.

3. A disappearing stairway comprising the combination with a panel hinged at one edge of a ceiling opening, of a stair structure pivoted at its upper end so as to be movable with the panel, said stair structure comprising a plurality of tread carrying stringers pivoted together at their ends and supported on the panel so that the sections may be swung upwardly in the manner of a toggle and the lower end of the stair structure drawn upwardly onto the panel whereby the stair structure may move with the panel to a position in the ceiling opening above the panel when the panel is shut.

4. A disappearing stairway comprising the combination with a movable panel closure for a ceiling opening, of a stair structure supported at its upper end so as to be movable with the panel, said stair structure comprising sections pivoted to each other and sup-

ported on the panel so that the sections may be swung upwardly in the manner of a toggle and the lower end of the stair structure drawn upwardly onto the panel whereby the stair structure may move with the panel to a position in the ceiling opening above the panel when the panel is shut, and means for operating said panel and stair structure, comprising an arm pivoted on the panel and having a slidably, non-pivotal connection with the lower stair section, a sheave on the arm and cable means trained about said sheave and connected to the lower stair section. 70

5. A disappearing stairway comprising the combination with a panel hinged at one edge of a ceiling opening, of a stair structure pivoted at its upper end so as to be movable with the panel, said stair structure comprising sections pivoted to each other and supported on the panel so that the sections may be 80 swung upwardly in the manner of a toggle and the lower end of the stair structure drawn upwardly onto the panel whereby the stair structure may move with the panel to a position in the ceiling opening above the panel 90 when the panel is shut, and means for operating said panel and stair structure comprising an arm pivoted on the panel and having a slidably, non-pivotal connection with the lower stair section, a sheave on the arm and cable means trained about said sheave and connected to the lower stair section. 95

6. A disappearing stairway comprising the combination with a movable panel closure for a ceiling opening, of a stair structure supported at its upper end so as to be movable with the panel, said stair structure comprising sections pivoted to each other and supported on the panel so that the sections may be 100 swung upwardly in the manner of a toggle and the lower end of the stair structure drawn upwardly onto the panel whereby the stair structure may move with the panel to a position in the ceiling opening above the panel when the panel is shut, means for 105 operating said stairway, said means being connected to the lowermost section, and a pivoted mounting on the panel on which the lowermost stair section is slidable. 110

7. A disappearing stairway comprising the combination with a panel hinged at one edge of a ceiling opening, of a stair structure pivoted at its upper end so as to be movable with the panel, said stair structure comprising sections pivoted to each other and supported on the panel so that the sections may be 115 swung upwardly in the manner of a toggle and the lower end of the stair structure drawn upwardly onto the panel whereby the stair structure may move with the panel to a position in the ceiling opening above the panel when the panel is shut, means for operating said stairway, said means being connected to the lowermost section, and a pivoted 120

mounting on the panel on which the lower-most stair section is slid able.

8. The combination with a disappearing stairway adapted to be moved between a retracted position and an extended position of

5 use in cooperation with a ceiling opening, of power driven means for extending and reTRACTING said stairway, said means including a motor, a cable drum having a cable thereon

10 connected to the stairway, reversing clutch means between the motor and cable drum, means for starting the motor, means operable by movement of the stairway into its extended position to stop the motor and to

15 reverse the clutch, and means operable by movement of the stairway into its retracted position to stop the motor and to reverse the clutch.

9. The combination with a disappearing 20 stairway adapted to be moved between a retracted position and an extended position of use in cooperation with a ceiling opening, of power driven means for extending and reTRACTING said stairway, said means including

25 a motor, reversing clutch means, means for starting the motor, means operable by movement of the stairway into its extended position to stop the motor and reverse the clutch, and means operable by movement of the

30 stairway into its retracted position to stop the motor and to reverse the clutch.

10. The combination with a disappearing stairway movable between a retracted position and an extended position of use in co-

35 operation with a ceiling opening, of power means for operating said stairway between said positions, reversing clutch means controlling the operation of the stairway between said positions by the power means, and

40 means operable by the stairway as it moves into each of said positions for stopping the power means and reversing the clutch means.

11. The combination with a disappearing stairway movable between a retracted posi-

45 tion and an extended position of use in co-operation with a ceiling opening, of power means for operating said stairway between said positions, reversing clutch means controlling the operation of the stairway be-

50 tween said positions by the power means, and means operable by the stairway as it moves into each of said positions for reversing the clutch means.

12. The combination with a disappearing

55 stairway movable between a retracted position and an extended position of use in co-operation with a ceiling opening, of power means for operating said stairway between said positions, reversing clutch means con-

60 trolling the operation of the stairway be-

tween said positions by the power means, and means operable by the stairway as it moves into each of said positions for stopping the power means.

65 13. A disappearing stairway comprising a

stair structure movable in cooperation with a ceiling opening between retracted and extended positions, said stairway including toggle jointed stair sections, and means for extending and collapsing said sections.

70 14. A disappearing stairway comprising a

stair structure movable in cooperation with a ceiling opening between retracted and extended positions, said stairway being pivoted to swing as a unit about its upper end and including toggle jointed stair sections, and means for extending and collapsing said sections.

75 15. A disappearing stairway comprising a

stair structure movable in cooperation with a ceiling opening between retracted and extended positions, said stairway including toggle jointed stair sections, and means for extending and collapsing said sections, said

80 means comprising a reversible power driven member and means controlled by extension and retraction of said stairway for stopping said driven member and setting it for reverse drive.

85 16. A disappearing stairway comprising a

stair structure movable in cooperation with a ceiling opening between retracted and extended positions, said stairway including toggle jointed stair sections, and means for extending and collapsing said sections, said means comprising a motor and reversible clutch means, and means controlled by extension and retraction of the stairway for stopping the motor and reversing the clutch.

90 17. The combination with a disappearing

stairway adapted to be moved between a retracted position and an extended position of use in cooperation with a ceiling opening, of power driven means for extending and reTRACTING said stairway, said means includ-

95 ing a motor, a cable drum having a cable thereon connected to the stairway, reversing clutch means between the motor and cable drum, manually operable switches at each

100 floor between which the ceiling opening is located for starting the motor, a switch for stopping the motor, means operable by movement of the stairway into its extended position to operate the last-named switch and to

105 reverse said clutch and means operable by movement of the stairway into its retracted position to operate said last-named switch and to reverse the clutch, said last-named

110 switch and said manually operable switches being so arranged in a circuit with the motor that the former upon stopping the motor sets connections between the latter whereby the subsequent operation of either of the manually operable switches will start the motor.

115 18. The combination with a disappearing

stairway adapted to be moved between a retracted position and an extended position of use in cooperation with a ceiling opening, of power driven means for extending and

retracting said stairway, said means including a motor, reversing clutch means, manually operable switches at each floor between which the ceiling opening is located for starting the motor, a switch for stopping the motor, means operable by movement of the stairway into its extended position to operate the last-named switch and to reverse said clutch and means operable by movement of the stairway into its retracted position to operate said last-named switch and to reverse the clutch, said last-named switch and said manually operable switches being so arranged in a circuit with the motor that the former upon stopping the motor sets connections between the latter whereby the subsequent operation of either of the manually operable switches will start the motor.
